UNITED STATES PATENT OFFICE.

RICHARD HENRY STEVENS, OF CHIGWELL, AND TIMOTHY HALL, OF ROMFORD, ENGLAND.

SPRING FOR VEHICLES.

No. 878,429.

Specification of Letters Patent.

Patented Feb. 4, 1908.

Application filed December 28, 1906. Serial No. 349,911.

To all whom it may concern:

Be it known that we, RICHARD HENRY STEVENS, subject of the King of Great Britain, residing at Chigwell, Essex, England, and TIMOTHY HALL, subject of the King of Great Britain, residing at Romford, Essex, England, have invented certain new and useful Improvements in or Relating to Springs for Vehicles, of which the following is a specification.

Our invention relates to vehicle springs applicable more particularly to road vehicles and the said invention provides a novel combination with the ordinary metal springs of air-cushions arranged in telescopic protective casings. It is already known to employ air-cushions in road vehicles to improve the smooth running of the vehicle, but such air-cushions have not heretofore been combined with the ordinary metal springs in the manner hereinafter described so as to enable the metal springs to continue to serve their purpose even should the air-cushions be deflated.

The telescopic casings in our invention are arranged longitudinally of the vehicle one in conjunction with each metal spring, and one part of each casing is secured to the metal spring and the other part to the axle. By this arrangement if one or more of the air-cushions should become deflated, the body of the car would still be supported by the ordinary metallic spring or springs so that it would only be necessary to deflate the air-cushion or cushions on the opposite side of the vehicle in order to restore the body of the vehicle to a suitable running condition. This deflation will take place automatically if the air-cushions are interconnected as hereinafter described.

The telescopic casings for inclosing the air-cushions each consist of two shells preferably of metal one of which slides in the other, means such as anti-friction rollers being provided for reducing friction at the places where the driving force is transmitted from the body of the vehicle to the axle, or vice versa.

In the accompanying drawing, we have shown how our said invention may be conveniently and advantageously carried into practice.

Figure 1 is a longitudinal section through the telescopic casing and its inclosed air-cushion, and Fig. 2 is a transverse section on the line X, X, Fig. 1. Fig. 3 is a view

showing the improved combination of a metal spring and an air-cushion applied to a road vehicle.

Like letters of reference denote corresponding parts in the three figures.

A denotes the ordinary metal spring which is bolted to the box or casing B which contains the air-cushions C. Within the box B is a sliding part D which can slide freely within the box, the two parts B, D together forming the telescopic casing which completely incloses the air-cushion C. To facilitate the movements of the part D the same is provided with rollers E, E that roll on the end walls of the box B and make the movement easy and free. If necessary additional rollers can be provided on the box B to bear on the part D near its upper edges or corners.

F is the axle shown bolted to the sliding part D of the telescopic casing.

G, G are transverse rods or bolts supporting the sides of the box B. The upper pair of these transverse rods also limits the expansive movement of the telescopic casing. The end wall b of the box B is made removable to admit of taking out the air-cushion and reinserting it when desired without interfering with the vehicle; the valve H of the air-cushion is shown projecting through the sliding part D of the telescopic casing where it can be easily reached for inflating purposes. In order the better to protect the air-cushion we prefer to make the sides of the part D somewhat taper as shown.

In some cases, the air-cushion or bag C is made of flexible but non-extensible material and of rounded or oblong form, so as not to extend near to the edge of the inner part of the casing relatively to which the outer part of the casing moves, thus avoiding wear of the said cushion or bag by the relative motion, and also preventing nipping of the cushion or bag between the said edge and the wall of the outer part of the casing.

It will be understood that one such arrangement as that described will be combined with each spring of the vehicle, and the same may be independent of each other and be inflated separately.

As shown in Fig. 3 of the accompanying drawings, springs A and casings B, D containing air-cushions C are shown superposed between the vehicle body K and each of the axles F. If desired however, the several air-bags used on a vehicle may be put into com-

munication with each other through a suitable pipe or pipes so that they may be pumped up simultaneously. Or if desired the air-cushions above the rear wheels of a 5 four-wheeled vehicle may be connected together and the air-cushions above the front wheels may be connected together, since it may be desired to carry different weights on the front and rear wheels respectively. In 10 such arrangements valves are preferably provided to enable the several air-cushions to be cut off from communication with each other after they have been pumped up. Gage-marks may be provided on the relatively movable parts of the telescopic casings 15 to indicate the extent of inflation of the air-cushions. The inflation may be effected by a hand pump or by a pump driven by the motor of a motor-vehicle or through suitable 20 gearing from one or more of the wheels of the vehicle. By our said invention, solid elastic or other tires may be used without causing undue vibration to be transmitted to the body of the vehicle.

25 What we claim is:—

1. The combination of a vehicle body and axle, a metal spring, an air cushion, a telescopic casing inclosing said air-cushion and comprising two shells which are elongated in 30 the direction of the length of the vehicle and which fits loosely one within the other at their sides, anti-friction rollers for connecting said shells and transmitting the horizontally-acting tractive forces from one shell to the other, means for securing said metal spring directly to one of said shells, and means for 35 connecting said metal spring and said casing in their united condition between the axle

and the vehicle body, substantially as described.

2. The combination with a vehicle body and an axle, of a metal spring, an air cushion, a telescopic casing containing said air cushion and comprising inner and outer parts, rollers arranged to reduce frictional resistance to 45 relative motion of the parts of said telescopic casing, one wall of the outer part of said casing being removable, means for securing said metal spring directly to one part of said casing, and means for connecting said metal 50 spring and said casing in their united condition between the axle and the vehicle body, substantially as described.

3. The combination of a vehicle-body and axle, a metal spring, an air-cushion, a telescopic casing inclosing said air-cushion and comprising two shells which are elongated in 55 the direction of the length of the vehicle and which fit loosely one within the other at their sides and of which the outer shell has a removable end-wall, anti-friction rollers for connecting said shells and transmitting the horizontally-acting tractive forces from one shell to the other, means for securing said metal spring directly to one of said shells, 60 and means for connecting said metal spring and said casing in their united condition between the vehicle and the axle-body.

In testimony whereof we have hereunto set our hands in presence of two subscribing 70 witnesses.

RICHARD HENRY STEVENS.
TIMOTHY HALL.
